UNITED STATES PATENT OFFICE.

WILLIAM WARING, OF QUINCY, MASSACHUSETTS, ASSIGNOR TO NATIONAL BRAKE & CLUTCH COMPANY, OF BOSTON, MASSACHUSETTS, A CORPORATION OF MAINE.

POWER-TRANSMISSION DEVICE.

988,607.

Specification of Letters Patent.

Patented Apr. 4, 1911.

Application filed October 20, 1910. Serial No. 588,169.

To all whom it may concern:

Be it known that I, WILLIAM WARING, a citizen of the United States, residing in Quincy, county of Norfolk, and State of 5 Massachusetts, have invented an Improvement in Power-Transmission Devices, of which the following description, in connection with the accompanying drawings, is a specification, like letters on the drawings 10 representing like parts.

This invention relates to a power transmission device of that class in which a series of contacting members are attached to an endless belt and engage at their ends with 15 driving and driven members or disks.

The present invention has for its object to increase the efficiency of apparatus of the class described, and to render the same effective in the presence of oil, moisture, etc. 20 To this end, the contacting members carried by the endless belt are provided at their ends with one or more sockets into which are forced under compression inserts of cork, which are designed to contact with the driving 25 and driven members, whereby the frictional engagement between the endless belt and the driving and driven members is greatly increased and the driving power of the device is increased, and is unimpaired 30 by the presence of oil, moisture, etc.

Figure 1 is a plan view of a power transmission device embodying this invention. Fig. 2, a detail in section on an enlarged scale to be referred to. Fig. 3, a detail in 35 side elevation of the endless conveyer, and Fig. 4, a modification to be referred to.

Referring to the drawings, *a* represents an endless belt or band of leather, canvas or like material to which is secured a series of 40 blocks *b* of wood or other suitable material by bolts *c*, which are passed through the blocks *b* and through strips or bars *d* of wood or other suitable material which are located on the side of the belt *a* opposite to the 45 blocks *b*. The endless belt *a* with its attached blocks *b* acts to transmit power from a driving member to a driven member. The driving member consists of a pair of metal disks 10, 12, having hubs 14, 15, which are 50 splined on a shaft 16 to rotate therewith and to slide thereon toward and from each other, said disks being beveled or inclined outwardly from their hubs to their circumferences. The driven member consists of

like disks 20, 21, provided with hubs 22, 23, 55 mounted on a shaft 24 to be driven and splined thereon to be moved toward and from each other. The hubs 14, 22 have pivotally connected to them a lever 26, which is pivoted at 27 between said hubs, and the 60 hubs 15, 23 have pivotally connected to them a lever 28, which is pivoted at 29, said levers being connected together by a rod 30. The free ends of the levers 26, 28 are connected to an actuating rod 31, by means of which 65 said levers may be moved simultaneously to move the hubs 14, 15, in the opposite direction to that in which the hubs 22, 23 are moved and vice versa, so as to vary the speed of the driven member. 70

The blocks *b* are provided with inclined or beveled ends to conform to the bevel of the disks with which they coöperate, and said ends may be provided with facing pieces 33 of leather or other flexible, fibrous material, as shown in Figs. 2 and 3, or said facings may be omitted as shown in Fig. 4. The blocks *b* in either case are provided in their ends with one or more sockets 35 into which are inserted under compression one 80 or more inserts 36 of cork, which are designed to make contact with the metal disks, and thereby increase the frictional contact of the blocks *b* with the disks. The cork inserts may and preferably will be made 85 slightly longer than the depth of the sockets, so that they project beyond the surface of the block and yieldingly engage the metal disks. By means of the cork inserts, the efficiency of the endless belt for transmitting power from the driving disks to the 90 driven disks is greatly increased and maintained at its maximum efficiency for substantially the life of the belt. Furthermore, this efficiency is maintained even in 95 the presence of oil, moisture, etc., which enables the transmission device to be used in many places where it otherwise could not be used.

The disks 10, 12, may be the driving member, and the disks 20, 21, the driven member, and the speed of the latter can be regulated by manipulating the levers 26, 28, so as to move the disks toward and from each other to thereby vary the point of contact of 105 the conveyer with the said disks.

I may prefer to use the leather facings 33 and to extend the corks through them, in

which case the frictional efficiency of the leather is obtained in addition to that of the cork, but it is not desired to limit the invention in this respect, as the leather facing may 5 be omitted, as shown in Fig. 4. In either case, the slipping of the endless belt between the disks, either of the driving or the driven member, is avoided, and the efficiency of the apparatus is greatly increased in normal or dry conditions of use, and in abnormal or wet conditions due to the presence of moisture or oil on the disks, the apparatus is rendered effective and its efficiency as a power transmitter is maintained.

15 Claims:

1. A power transmitting device comprising an endless belt, and a series of blocks attached to said belt and provided with sockets in their opposite ends and with facing 20 pieces of flexible fibrous material having holes in line with said sockets, and corks inserted into said sockets and extended through said facings substantially flush with the outer surface thereof, substantially 25 as described.

2. A power transmitting device comprising an endless belt and a series of contacting members attached thereto and provided in their ends with sockets and inserts of cork 30 extended into said sockets and forming

part of the contacting surfaces of the ends of said members, substantially as described.

3. A power transmitting device comprising an endless belt and a series of blocks attached thereto and provided in their ends with sockets and inserts of cork extended into said sockets and forming part of the contacting surfaces of the ends of said blocks, substantially as described. 35

4. In a power transmitting apparatus, an endless belt and a series of blocks attached thereto and provided in their ends with sockets and inserts of cork extended into said sockets and forming part of the contacting surfaces of the ends of said blocks, substantially as described. 40

5. A power transmitting device comprising an endless belt and a series of blocks attached thereto and provided with sockets, and inserts of cork inserted into said sockets 50 and forming part of the contacting surface of said blocks.

In testimony whereof, I have signed my name to this specification in the presence of two subscribing witnesses.

WILLIAM WARING.
